UNITED STATES PATENT OFFICE.

EDMUND ROGERS, OF CHICAGO, ILLINOIS, ASSIGNOR OF ONE-HALF TO THOMAS J. MARTIN, OF CHICAGO, ILLINOIS.

TIME-CALLING DEVICE FOR TELEPHONES.

1,244,081.

Specification of Letters Patent. Patented Oct. 23, 1917.

Application filed June 13, 1916. Serial No. 103,482.

To all whom it may concern:

Be it known that I, EDMUND ROGERS, a citizen of the United States, residing at Chicago, in the county of Cook and State of Illinois, have invented certain new and useful improvements in Time-Calling Devices for other subscriber should call the same station. Telephones, of which the following is a specification. With these and other objects in view, my invention will be more fully described, illustrating.

My invention relates to new and useful improvements in telephone attachments, the primary object of my invention being the provision of what I term a time calling device which may be employed in connection with a telephone system and which is capable of being cut in and out of circuit with the line.

Frequently, a subscriber repeatedly calls on the line 2—2 of Fig. 5, tempts to call another subscriber who, during the time, is out. My invention is designed to automatically transmit a signal to the calling subscriber of such a character as to indicate at what time the subscriber whose station is being called will be able to answer. In other words, my device is of such a nature that the person having it in connection with a telephone instrument may, when leaving the building, cut the device out of the telephone and set the device to transmit a signal indicating any desired hour of the day, the signaling mechanism being so arranged as to be released and operated upon the closing of the telephone circuit, such as occurs when one subscriber calls another.

More specifically, my invention comprehends a movable contact carrying member having a plurality of contacts arranged in series and an adjustable contact member having a contact movable to project into the path of the contacts of any desired series, the provision of means for releasing and driving the movable contact carrying member when a circuit is closed through the instrument.

One of the objects of my invention consists in providing each of my time calling devices with a buzzer or other sound producing device which may be energized by engagement of these contacts with a transmitter connected, when the device is in operation, in the telephone circuit so that signals sounded by the buzzer will be transmitted to the telephone instrument of any station upon the line.

A still further object of my invention consists in providing means for automatically locking the movable contact carrying member after the signal has been given in order to prevent noise, have invented certain new and useful that the device may again operate if an

Improvements in Time-Calling Devices for other subscriber should call the same station.

With these and other objects in view, my invention will be more fully described, illustrating.

My invention relates to new and useful improvements in the accompanying drawings, and

improvements in telephone attachments, the primary object of my invention being the provision of what I term a time calling device which may be employed in connection with a telephone system and which is capable of being cut in and out of circuit with the line.

In the drawings:

Figure 1 is a front elevation of my time

device; Figure 2 is a vertical sectional view taken

on the line 2—2 of Fig. 5;

Fig. 3 is a corresponding sectional view

taken on the line 3—3 of Fig. 5;

Fig. 4 is a front elevation, with part of

the casing broken away to show certain de-

tails in structure;

Fig. 5 is a vertical sectional view taken

on the line 5—5 of Fig. 1;

Fig. 6 is a diagrammatic view of the

wiring of the device;

Fig. 7 is a diagrammatic view of the wir-

ing into the telephone circuit, thereby cutting

off a subscriber's station equipped with

the telephone and set the device to trans-

mit a signal indicating any desired hour

Corresponding and like parts are referred

to in the following description and indi-

cated in all the views of the drawings by

the same reference characters.

My improved time calling device includes

a suitable electrically operated mechanism

which is preferably inclosed in a casing

which may be formed of any desired ma-

terial and the front wall 11 of which is pro-

vided with a circular opening 12 to receive

the retaining ring 13 of a conventional form

of clock dial 14, closed by a glass face plate

15. Secured to the inner face of the wall

is a bracket 16 of insulating material which

includes the spaced supporting plates 17

joined at their lower ends to provide a tubu-

lar sleeve 18 vertically disposed within the

casing. A bearing 19 is fitted in the for-

ward plate of the bracket 16 and a bearing

20 is secured to the rear plate, a

shaft or arbor 21 being journaled in these

bearings and provided with an indicating

hand 22 projecting through the dial and

through the face plate 15 and carrying at its

outer end a milled nut 23 by means of which

the shaft may be turned to bring the hand 11

22 opposite any desired division or fractional division of the dial. Within the casing, the shaft 21 carries a pinion 24 which meshes with the teeth of a rack bar 25 having a cylindrical lower portion which is slidably mounted in a contact sleeve 26 of brass or other suitable metal fixed within the insulating sleeve 18 by means of a set screw 27. This rack bar, at its lower terminal, 19 is provided with a rearwardly directed, preferably resilient, contact finger or brush 28.

Front and rear frame plates 29 and 30 are supported upon the bottom of the casing 10 and journal a shaft 31 about which is 15 wound a spiral spring 32, one end of which is fixed to the shaft and the other end of which is formed to provide a loop 33 through which is passed an anchoring rod 34 carried by the frame members 29 and 20 30. Loosely mounted upon the shaft 31, is a spur gear 35 and fixed upon the shaft is a ratchet wheel 36. The gear carries a pawl 37 which is constantly held in engagement with one or another of the teeth of the 25 ratchet wheel by a spring 38 also carried by the gear. Because of this arrangement, the shaft 31 may be turned in one direction to tension the spring 32 without turning of the gear, while the shaft can turn in the 30 other direction only if the gear is free to turn. The forward end of the shaft is square, as shown at 39 in Fig. 5, to receive a winding key 40, the shank of which may be passed through an opening 41 formed 35 in the front of the casing for this purpose. A second shaft 42 is mounted in the plates 29 and 30 and carries a pinion 43 meshing with the gear 35 and a gear 44 which meshes with a pinion 45 carried by a shaft 46 mounted 40 in the plates, all of these shafts extending parallel to each other.

Fixed upon the forward end of the shaft 46, is a contact carrying member or disk 47, the peripheral edge of which is provided 45 with a notch 49 to seat the free end of a combined latch and armature 50 which is pivoted upon a bracket 51 carried by the plate 30 but insulated therefrom, as shown at 52. A second bracket 53 is carried by 50 but insulated from the plate 29 and a helical spring 54 is connected at one end to this second bracket and at its other end to the latch and armature 50 to normally hold its terminal in the notch 49 and so hold the 55 disk 47 against rotation, due to the action of the spring 32. Obviously, if this latch is released, the spring 32 will act through the train of gears and pinions, above described, to rotate the disk 47 until such rotation is 60 stopped by reengagement with the latch in the notch of the disk.

Arranged upon or formed integrally with the contact carrying disk 47 are a plurality of contacts adapted to be engaged by the 65 contact brush 28. These contacts are ar-

ranged in radially spaced series, the contacts of each series being circumferentially spaced and curved from end to end so that they are concentric with respect to the disk, as clearly shown in Fig. 4. Certain of these 70 contacts, as the contacts 55, are longer than the other contacts, such as the contacts 56, so that when the disk is revolved and the contact brush 28 is in position to engage the contacts of any one of the series, the circuit 75 will be successively closed and opened, the periods of time during which it is closed being dependent upon the length of the contacts engaged by the contact brush. The contact carrying disk shown in Fig. 4 is 80 one having contacts arranged to signal any hour and half hour. For instance, disposed next to the axis of the disk is a single long contact 55. If the contact brush carrying rod is lowered so that the brush will engage 85 this inner long contact 55, the circuit will be closed but once for a rotation of the disk. The next adjacent series consists of a single long contact 55 followed by a short contact 56, the next adjacent series of two long contacts 55, the next series of two long contacts and a short contact and the like, the outer series consisting of twelve long contacts followed by a short contact. The long contacts are intended to close circuits in such a manner as to indicate hours, each contact indicating one hour and the short contacts to indicate half hours. By adjusting the contact brush 28 to the proper position radially of the disk, the rotation of the disk will 90 cause a circuit to be successively closed and opened, which will indicate the desired hour and half hour through mechanism to be later described. Obviously, by governing the number of series and by having the short 95 contacts indicate quarter hours and properly arranging such short contacts with respect to the long contacts, circuit may be closed to indicate any desired time of the hour and quarter hour.

110 A battery 57 of any suitable type is employed in connection with this device and may or may not be inclosed in the casing, as preferred. A wire 58 leads from one pole of this battery to any suitable binding post 115 59 carried by one of the plates 29 or 30, with the result that current may flow from the battery to the disk 47 and contacts carried by the disk. A second wire 60 leads from the opposite pole of the battery to one of the binding posts of any suitable type of sound producing device, such as a buzzer 61 and a wire 62 leads from the other binding post of this buzzer to the set screw 27. As a result, whenever the brush 28 engages 120 any one of the contacts carried by the disk 47, a circuit will be closed from the battery through the wire 58, contact disk and that contact on the disk engaged by the brush 28, through the brush 28, rod 25, sleeve 26, 125 130

binding post 27, wire 62, buzzer 61, and wire 60 to the battery.

Disposed within the casing, with its mouth-piece in juxtaposition to the buzzer 61, is a 5 telephone transmitter 63 of conventional type, the binding posts 64 and 65 of which project through the wall of the casing adjacent an additional binding post 66. A wire 67 leads from the binding post 66 to a 10 contact 68 carried by a bracket 69 of insulating material secured within the casing and a wire 70 leads from a second contact 71 carried by the same bracket to an electro-magnet 72 supported by a bracket 73 carried by the back plate 30, a wire 74 leading from this magnet to the binding post 64. It will, therefore, be seen that if a circuit is closed, including the binding posts 64 and 66, bridging of the contacts 68 and 71 15 will permit closing of a circuit through the electro-magnet 72 and consequent attraction of its armature which is the combined latch and armature 50, previously described. The closing of such a circuit will, therefore, act to release the disk 47 and permit its rotation through the action of the spring 32. The latch and armature 50 carries a sleeve 75 of insulating material which in turn carries a switch arm 76 formed with 20 a laterally directed head 77 having a downwardly projecting terminal 78 adapted in lowered position of the armature to bridge the contacts 68 and 71 and in attracted position of the armature to engage the contact 68 alone. This laterally directed head of the switch arm 76 is also formed with a contact stud 79 adapted to engage in the socket of a contact forming bracket 80 secured to the bracket 17 of insulating material and connected to the wire 67 by a branch wire 82. A conductor bracket 83 is secured to the plate 30, being insulated therefrom, as shown at 84, and terminates in a contact head 85 adapted to be engaged 25 by the rod 76 when the armature 50 is raised, due to swinging of the rod because of the pivotal mounting of the armature. A wire 86 leads from this conductor bracket 83 to the binding post 65.

30 The above structure comprises my time calling attachment for telephones, but before describing its operation, I wish to explain the manner in which it is connected in the telephone circuit with the usual telephone instrument. For this purpose I provide a pivotally mounted switch blade 87 to which one of the telephone line wires 88 leads, the other telephone line wire 89 leading directly to the telephone 90 in the usual 35 manner. Also mounted upon the casing, at one side of the switch blade, are spaced contacts 91 between which the switch blade may be wedged and at the free side of the switch blade spaced contacts 92 also adapted 40 to be engaged by the switch blade. A wire

45 leads from the contacts 91 to the telephone instrument and with the switch blade in the position shown in Fig. 7 forms a continuation of the line wire 88, my attachment being cut out when the switch 87 is 50 in the position there shown. A wire 94 leads from the contacts 92 to the binding post 66 and a wire 95 leads from the binding post 64 to the line wire 89.

55 In describing the operation, I will first assume that my time calling device is connected with a telephone instrument in the manner shown in Fig. 7. Under these conditions, the device is inoperative as no current passes to it, the telephone instrument being 60 directly connected with the line wires 88 and 89 through the switch 87 and wire 93. Under these circumstances, the telephone instrument will be employed in the usual manner. If the telephone subscriber at the station in which my device is installed expects 65 to be absent for any length of time, such subscriber will set the indicating hand or needle 22 at the hour and fractional part 70 of the hour of expected return and will 75 swing the switch 87 to a position opposite that shown in Fig. 7. This setting of the indicating hand 22 will bring the contact brush 28 opposite the proper series of time 80 signaling contacts upon the disk 47 while the 85 changing of the switch 87 will cut out the telephone instrument 90 and cut in my calling device. Under these circumstances, 90 if central connects any calling subscriber 95 with the telephone instrument so set, current will pass over the line wire 88 through the switch 87 and wire 94 to the binding post 66 of my device, from this binding post 100 through the wire 67 and bridged contacts 68 and 71 and wire 71 to the electro-magnet 72, 105 from this magnet through the wire 74 to the binding post 64 and from the binding post 64 through the wire 95 to the return line wire 89. The circuit thus closed will 110 energize the magnet 72, raising the combined latch and armature 50. The raising of this armature will act to release the contact carrying disk 47, which will then be driven by the spring 32 to move the contacts 115 of the selected series successively into engagement with the contact brush 28 to close a certain predetermined series of circuits through the buzzer 61. At the same time, the raising of the armature 50 will raise the contact head 77 into engagement with the 120 contact 80 and the contact 85 and out of engagement with the contact 71, thereby breaking the circuit through the magnet and closing a circuit from the line wire 88, through the switch 87, wire 94, wire 67, wire 82, contacts 80, 77 and 85, wire 86, transmitter 63 and wire 95 back to the return line wire 89. This circuit being closed, the sounds produced by the buzzer will be transmitted over 125 the line wire and heard by the calling sub- 130

scriber who may thus determine at what time the call should be repeated to reach the party desired. Although the circuit through the electro-magnet 72 has now been broken, 5 as explained, the armature 50 is still held in raised position by its engagement with the periphery of the disk 47 and the circuit through the transmitter is, therefore, kept closed until the disk 47 has completed one 10 revolution, when the armature will drop into the notch 49 of the disk to lock the disk against further movement, to open the circuit through the transmitter between the contacts 77 and 80, and to bridge the contacts 15 68 and 71. By the time that the disk 47 has completed its revolution, however, a signal will have been received by the calling station and such station will have hung up its receiver and, consequently, cut off the line 20 so that the magnet 71 will not be reenergized upon bridging of the contacts 68 and 71 unless the station having my instrument is again called.

From the foregoing description, it will be 25 apparent that I have provided a time signaling attachment for telephones which does not in any way interfere with the ordinary employment of the telephone which may be set by a subscriber in such a manner that another station calling a subscriber will be notified when to again call to find the party 30 called at home.

It will further be apparent that my device is so constructed that any desired time of 35 day or night may be signaled by it and so arranged that when once set is automatic in its action, being set in action by the closing of the circuit in which it is attached and acting to automatically stop and reset itself 40 after the signal has been given. Obviously, many changes in details of construction may be made without affecting the operation of the device and I, therefore, reserve the right to make any changes, within the scope of the 45 appended claims, without departing from the spirit of my invention.

Having thus described the invention, what is claimed as new is:

1. The combination with a telephone instrument and circuit therefor, of a transmitter, an electro-magnet, means for cutting the telephone instrument out of the telephone circuit and the magnet into the telephone circuit, a revolvably mounted contact carrying disk, means constantly tending to drive the disk, the disk carrying a plurality of series of spaced contacts, a movable contact, means including an indicator for shifting the movable contact to bring it into the path 50 of movement of any one of the series of contacts, a sounding device in an open energized circuit including the movable contact and the contact disk, an armature for the magnet normally holding the disk against turning 55 movement, and means actuated by movement

of the armature to release the disk for placing the transmitter in the telephone circuit.

2. The combination with a telephone instrument and circuit therefor, of a transmitter, an electro-magnet, means for cutting the telephone instrument out of the telephone circuit and the magnet into the telephone circuit, a contact carrying disk mounted for rotation and formed in its peripheral edge with a notch, an armature for the magnet 70 adapted to seat in the notch when the magnet is unenergized to hold the disk and adapted to be held in raised position by the disk during turning of the latter, means constantly tending to turn the disk, a plurality 75 of series of contacts carried by the disk, a movable contact engageable with the contacts of each series, means including an indicator for selectively shifting the movable contact so that it may engage the contacts of 80 any desired series, a sounding device, an energized circuit including the sounding device, contact disk and movable contact and normally open between the movable contact and the contacts of the disk, and means operable upon energization of the magnet for connecting the transmitter in the telephone circuit.

3. The combination with a telephone instrument and circuit therefor, of a transmitter, an electro-magnet, means for cutting the telephone instrument out of the telephone circuit and the magnet into the telephone circuit, an armature for the magnet, an audible signal producing mechanism normally 90 locked by the armature, releasable upon movement of the armature through attraction of the magnet and capable of holding the armature in attracted position until the signal has been completed, and means operable upon closing of a circuit through the magnet for breaking the circuit through the magnet and connecting the transmitter in the telephone circuit.

4. The combination with a telephone instrument and circuit therefor, of a transmitter, an electro-magnet, means for cutting the telephone instrument out of the telephone circuit and the magnet into the telephone circuit, and means operable upon energization of the magnet through energization of the telephone circuit for connecting the transmitter in the telephone circuit and giving an audible signal in juxtaposition to the transmitter, said means being adjustable 110 whereby any one of a predetermined number of different signals may be given and including a disk normally locked by magnet controlled means, means constantly tending to rotate the disk, a plurality of contacts 115 concentrically arranged about the disk in radially spaced series, a rod mounted for reciprocation and carrying a contact brush movable to extend in the path of any series, means including a rotatable indicator car. 120 125 130

rying shaft for adjustably reciprocating the rod, an electric audible signal device, and an energized circuit including the signal device, rod and disk and normally open between the contact carried by the rod and those carried by the disk.

5. A device of the character described, an electro-magnet adapted to be cut into a telephone circuit, an armature for the magnet, 10 an audible signal producing mechanism normally locked by the armature, releasable upon movement of the armature through attraction of the magnet and capable of holding the armature in attracted position until 15 the signal has been completed, and means operable upon closing of a circuit through the magnet for immediately breaking such circuit.

6. The combination with a telephone instrument and circuit therefor, of a transmitter, means operable by the transmission of a 20

ringing impulse over the telephone circuit for cutting the transmitter into such circuit and means operable upon the cutting in of the transmitter to sound an audible signal 25 indicating a predetermined time, such means being capable of giving relatively long sounds to indicate hours and relatively short sounds to indicate fractional portions of an hour.

7. The combination with a telephone circuit, of an electromagnet in the circuit, a transmitter, an electrically operated audible signal mechanism, means normally rendering the signal mechanism inactive, and 30 means operable upon energization of the electromagnet for rendering the signal mechanism active, cutting the transmitter into the telephone circuit and for breaking the circuit to the electromagnet.

40 In testimony whereof I affix my signature.

EDMUND ROGERS. [L. s.]
